(57) **CLAIM**

The ornamental design for a battery tester housing, as shown and described.

DESCRIPTION

FIG. 1 illustrates front perspective view of a battery tester housing.

FIG. 2 illustrates a front view of the battery tester housing illustrated in FIG. 1.

FIG. 3 illustrates a back view of the battery tester housing illustrated in FIG. 1.

FIG. 4 illustrates a side view of the battery tester housing illustrated in FIG. 1.

FIG. 5 illustrates another side view of the battery tester housing illustrated in FIG. 1.

FIG. 6 illustrates a top view of the battery tester housing illustrated in FIG. 1; and,

FIG. 7 illustrates a bottom view of the battery tester housing illustrated in FIG. 1.

The broken lines, when present in the drawings, represent portions of the battery tester housing. The broken lines are for the purpose of illustrating the environment of the design and form no part of the claimed design. The surface shading lines, when present in the drawings, show contour and/or distinguish between open and solid areas. The surface shading lines are not surface ornamentation.

1 Claim, 5 Drawing Sheets
